UNITED STATES PATENT OFFICE.

ALFRED E. PALMER, OF SAN FRANCISCO, CALIFORNIA, ASSIGNOR, BY DIRECT AND MESNE ASSIGNMENTS, TO HARRY E. LAMAR, OF OAKLAND, CALIFORNIA, AND MANUEL E. RAFAEL, OF SAN FRANCISCO, CALIFORNIA.

APPARATUS FOR PRINTING ON ROLL-PAPER.

SPECIFICATION forming part of Letters Patent No. 741,706, dated October 20, 1903.

Application filed December 4, 1902. Serial No. 133,877. (No model.)

To all whom it may concern:

Be it known that I, ALFRED E. PALMER, a subject of the King of Great Britain, and a resident of the city and county of San Francisco and State of California, have invented certain new and useful Improvements in Apparatus for Printing on Roll-Paper, of which the following is a specification.

This invention relates to improvements made in printing devices or apparatus that are specially devised for printing business-cards and advertising matter directly on a roll of wrapping-paper and are operated by the rotation of the roll on its supporting-frame as the paper is drawn from the roll. Devices of this character in which the type-carrying roller runs in contact with the roll of paper, making the impression directly upon the outer layer of the roll, are found to produce faint and uneven impressions on account of depressions and irregularities in the peripheral face of the roll and its variation from the shape of a true cylinder, and in practice these defects in the operation, particularly in printing on rolls of the larger sizes, have to a greater or less extent placed limitations on the length and size of the printing-roller, as well as the number, quantity, and the arrangement of the lines of type, while they also render uncertain the production of a clean and legible impression of the type on the paper as the roll becomes reduced in size.

The present improvements have for their object to overcome these defects and to produce a mechanism that will give a sharp and even impression on the paper under all changes in the size of the roll, unaffected by depressions or irregularities in the peripheral surface that cause it to vary from a true cylindrical form, also to enable these results to be attained on paper-rolls of all sizes and widths.

To such ends and objects my present invention consists in certain novel parts and combination of parts and in the production of an improved paper-roll-printing device or attachment, as hereinafter described, and pointed out in the claims at the end of this specification.

The improvements are clearly shown in the accompanying drawings, to which reference is had in the following description by the figures and letters thereon referring to the several parts.

Figure 1 of the drawings represents in perspective a frame and printing device for paper-rolls embodying my invention. Fig. 2 is a vertical cross-section through the frame and the printing mechanism, the dotted lines indicating the dimensions of the paper-roll at the time it is placed in the frame and when it has become reduced by being drawn off. Fig. 3 is a one-half front elevation, taken from the left side of Fig. 2, with a portion of one standard and the end of the roll-carrying spindle shown in section. Fig. 4 is a detail view of the roll-carrying spindle with one of its movable heads in section. Fig. 5 is an end view of the spindle, taken from the left of Fig. 4. Fig. 6 is a sectional view in detail of one of the spring-bearings of the printing-roller.

The two standards *a a*, united at the top by a cross-bar *b* and stiffened by a tie-rod *d* near the bottom, form a stationary frame such as is commonly provided for carrying paper-rolls of this description. Open sockets *e* on the inner sides of the standards furnish bearings for the ends of a spindle *f*, that is inserted and fixed in the center of the paper-roll, the ends of the spindle being easily set in and removed from the socket to place a fresh roll in the frame. Projecting from each standard a slotted arm *g*, preferably cast integrally with the standard, extends outward and upward at an angle from the vertical, and the two arms being parallel and inclined at the same angle furnish a support and bearings for the rollers that constitute the printing mechanism. This part of the device comprises the type-carrying roller or cylinder *h*, which I term the "printing-roller," a second roller *i*, placed between the printing-roller and the paper-roll and having a blanket or somewhat elastic or yielding surface, which I call the "impression-roller," and a third roller *k*, placed on the opposite side of the printing-roller that operates to ink the type.

on the face of the printing-roller. Bearings in the inner sides of the angular arms carry the journals of these three rollers, the bearings for the impression-roller being formed at the bottom of a recess or slot in each arm, but those for the printing-roller being formed in ⁵ slidable boxes *m*, upon each of which a coiled spring *p*, placed in the slot or recess above the box, is caused to bear with greater or less force by an adjustable screw-plug *r*, fitted to a threaded socket in the end of the arm. Any required degree of pressure between the printing-roller and the impression-roller below it is obtained by increasing or ¹⁰ reducing the force of the coiled spring through the medium of the screw *r*.

Instead of being arranged to bear directly on the circumference of the paper-roll, and thereby make the impression directly upon ²⁰ the outmost layer of the paper, it will be noticed in the present construction and arrangement that the printing-roller is always out of contact with the roll and the printing-surface works in contact with the impression-roller. In this arrangement the web of paper as it is drawn off the roll and before it is separated by the cutter *t*, usually provided in paper-roll carriers of this kind, is passed from the lower side of the paper-roll upward ³⁰ and between the impression-roller and the printing-roller before it is brought to the front and passed under the cutting-blade *t*, and consequently as the web of paper is drawn off the roll it operates to rotate mechanically by frictional contact the two rollers before mentioned, and the impression is made on that portion of the paper with which the type-carrying portions of the printing-roller surface comes in contact while running between ⁴⁰ it and the impression-roller. In this operation the surface of the impression-roller, which is always substantially a true cylinder, is substituted for the variable and constantly-changing surface of the paper-roll itself, with the effect to insure at all times, regardless of the varying changes taking place in the shape and diameter of the paper-roll, a sharp and even impression of the lines of type.

The printing-roller which I prefer to employ is the kind that has an inking-pad *h'* on a portion of its surface and the printing-type *h³* on the remaining portion. Rims or flanges *h²* on the ends of the roller outside the printing and ink-supplying surfaces run in contact with the impression-roller, so as to keep the printing-pad from touching the paper. These flanges are concentric with the axis of the roller and of uniform height all around the circumference. The proper contact of the ⁵⁰ type with the paper being secured by setting the face of the type sufficiently above the flange to give an even impression at that point in the rotation of the printing-roller where the type comes in contact with the paper presented by the impression-roller, the full pressure of the printing-roller is brought upon the type, whereas at all other parts in the

complete rotation of the printing-roller the flanges bear on the paper. The effect of this construction is to insure a clear impression ⁷⁰ of the first and the last lines or rows of type, because the difference in the height of the type over the flange is not sufficient to produce an abrupt change or jump at the point of contact with the impression-roller, and a ⁷⁵ practically smooth rolling contact is insured. The inking-roller is carried by bearings in the arms *g* above the printing-roller to run in contact with the inking-pad and over the type-surface in the usual manner. ⁸⁰

In apparatus of this description for printing on the web of wrapping-paper at the time it is drawn from the roll I have found that it is important to maintain an even tension on the web of paper after it leaves the roll and ⁸⁵ hold it at all times taut between the paper-roll and the printing-roller in order both to have the web travel evenly through the impression and printing rollers without running over one end or the other, and thereby ⁹⁰ insure a clean impression and uniform character of work under all the changes that in practice take place in the tension of the paper while it is being drawn off the roll, particularly with the widest and heaviest ⁹⁵ rolls, and the constant reduction in the size of the roll as the paper is drawn off for use. For that purpose I provide in the standard *a* and within the socket *e* a friction-brake consisting of a flat spring *w*, secured at one end ¹⁰⁰ to the side of the standard at a point above the socket and having its unattached lower end standing out from the back of the socket, so as to exert a constant pressure against the end of the spindle *f* when the latter is in the ¹⁰⁵ socket. A set-screw *2*, with a milled head and with the screw-threaded shank turned off smoothly to form a square end *3* of smaller diameter than the shank, is fitted to work in a threaded hole through the standard in line ¹¹⁰ with the longitudinal axis of the spindle, as seen in Figs. 2 and 3. The spring *w* is slotted or provided with an aperture *4* of smaller diameter than the threaded portion of the screw, so as to allow the reduced end to extend through the spring and set in a cavity in the end of the spindle. The screw thus ¹¹⁵ forms a center for the spindle to turn on and furnishes also a means for holding the paper-roll stationary when it is desired that paper should not be drawn therefrom by jamming the spring against the end of the spindle. A brake of this character at each end of the spindle will place the heaviest and largest paper-roll under such control that the roll ¹²⁰ will turn at every pull on the web in drawing it off a sufficient amount or extent to supply the desired length of paper and the roll will be each time arrested at the end of the rotation. Any additional movement that otherwise ¹²⁵ would be produced by the inertia of the roll, and particularly in the case of a large and heavy roll, is therefore prevented by the action of the brakes on the roll, and that por-

tion of the web which is unrolled and extends from the paper-roll to the printing-cylinder is maintained in a state of tension instead of being loose. When the roll is first introduced, and particularly with the widest and largest rolls which the apparatus is capable of handling, it will be found of advantage sometimes to apply a brake to the periphery of the roll just below the point where the outermost layer of the web separates from the next layer and runs over the impression-roller. This brake 5 is best formed of a piece of stiff wire bent to a rectangular shape to form the straight bar 5 and the side arms 5^a and the ends of the arms bent to form an eye 5^b, fitting loosely on the tie-rod *d* and attached to the arm 5^a to hold the brake-arm against the surface of the paper-roll with constant pressure under all variations in the diameter of the roll due to the consumption of the paper.

In order to insure the proper centering of the rolls in the frame, I have provided an adjustable spindle applicable to rolls of all sizes and capable of being tightly fitted in the roll for the time being, so that the roll and the spindle shall always turn together without liability of the paper turning on the spindle. The construction of this spindle will be understood from Figs. 3 and 4 of the drawings. The body of the spindle is a cylindrical rod *f*, with a recess 7 in each end for the center screw 2, and on each end is fitted a conical head 8, having its base or greatest diameter placed outward. These heads being fitted to slide longitudinally on the rod, they can be set toward or away from each other a greater or less distance, according to the width of the roll that is to be given on the spindle, and by virtue of the conical shape of the heads they act as wedges when forced into the center of the roll from opposite ends, and thus fix and hold the roll tightly on the spindle. Each conical head is held in position on the spindle by a spring-tongue 9, that is let into a groove 10 in the circumference of the rod and lengthwise of it and is arranged to set into a longitudinal slot or recess in the head, as seen in Figs. 3, 4, and 5. These springs lock the heads on the spindle, so that they always will turn together, and also serve to keep the heads in position against longitudinal movement.

Having thus fully described my invention, what I claim as new therein, and desire to secure by Letters Patent, is—

1. In a roll-paper-printing device, a supporting-frame, parallel slotted arms projecting from said frame and having tubular up-

per ends, an impression-roller journaled in bearings in the slots of said arms, a printing-roller also journaled in bearings in said slots, spiral springs located in the hollow portions of the arms and pressing against the bearings of the printing-roller, and means for adjusting the tension of said springs. 60

2. In a roll-paper-printing device, a supporting-frame, slotted arms projecting from said frame and having hollow tubular upper ends provided with a reduced internal-threaded portion, an impression-roller journaled in bearings in said slots, a printing-roller also journaled in bearings in said slots, spiral springs located in the hollow ends of the arms and pressing against the bearings of the printing-roller, and adjusting-screws in the reduced portions of said hollow ends bearing against the spiral springs. 70

3. In a paper-roll apparatus, the combination with a paper-roll to be supported, of a frame having sockets for the axle of the roll 80 to turn on, and an adjustable spindle applicable to paper-rolls of different widths, comprising a rod and conical heads longitudinally movable thereon and adapted to clamp the roll between them and fix it on the rod, and means for locking the heads on the spindle. 85

4. In a paper-roll apparatus, the combination with the supporting-frame, of an adjustable spindle journaled therein comprising a rod provided with longitudinal grooves, band-springs located in said grooves, and conical heads longitudinally movable on said rod and provided with internal longitudinal grooves adapted to receive said band-springs, whereby the heads are held against rotation upon the rod. 90

5. In a paper-roll apparatus, the combination with the supporting-frame and a spindle journaled therein and provided with hollow tubular ends; of a band-spring secured to the inner face of said frame and bearing upon the end of the spindle and provided with a free end having a perforation registering with the aperture in the end of the spindle, and a setscrew in said frame provided with a shank 100 bearing against the outer face of the band-spring and a reduced end passing therethrough and into the end of the spindle. 105

In testimony whereof I have signed my name in the presence of two subscribing witnesses. 110
